UNITED STATES PATENT OFFICE.

CHARLES BOISSET, OF NEW ORLEANS, LOUISIANA.

CORK-INSERTING MACHINE.

Application filed March 24, 1922. Serial No. 546,460.

To all whom it may concern:

Be it known that I, CHARLES BOISSET, a citizen of the French Republic, residing at New Orleans, in the parish of Orleans and State of Louisiana, have invented certain new and useful Improvements in Cork-Inserting Machines; and I do hereby declare the following to be a full, clear, and exact description of the invention, such as will enable others skilled in the art to which it appertains to make and use the same.

The present invention relates to improvements in cork inserting machines and more particularly refers to a machine for introducing cork inserts or the like into perforated clutch disks.

An object of the invention is to provide for the proper positioning and centering of the clutch disk so as to bring these perforations in sequence in a correct position to receive the insert and to allow of the rapid adjustment of the disk to bring subsequent perforations in registry with the cork inserting mechanism.

Another object of the invention resides in providing a machine of this character in which the mechanisms for centering and for holding the clutch disk centered and also for forcing the cork insert into the disk are so related and arranged as to be capable of easy and convenient operation and to permit of the manufacture of the device in a substantially condensed structure at an economical figure and to further permit rapidity in the operation of introducing the inserts and to provide for the correct application of the inserts to the disks.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a fragmentary view in side elevation and with parts shown in section of an improved cork inserting machine as constructed in accordance with the present invention;

Fig. 2 is an edge view of the same;

Fig. 3 is a section taken on the line 3—3 in Fig. 1;

Figs. 4 to 8 inclusive are enlarged frag-

mentary vertical sectional views of the inserting mechanism showing subsequent stages in the process; and,

Fig. 9 is a view of one of the disks with an insert in place.

Referring more particularly to the drawings, 1 designates a suitable table supported upon legs 2 in any desired manner and having an inverted L-shaped head stock 3 with the top portion over-hanging the table and secured at its base thereto as by the use of bolts 4.

The head stock carries a sleeve 5 with its axis disposed vertically and slidingly receiving a hollow stem 6 which acts as a guide for a cone carrier 7 extending downwardly therefrom toward the table and removably receiving a hollow cone 8 which is connected therewith as by the use of screw threads 9. The cone carrier 7 is provided with a forked or slotted lug 10 in which a pin 11 carried by a lever 12 is slidably received, the lever 12 being pivoted as at 13 to the head stock 3 and normally coming to rest upon a stop 14 projecting sidewise from the head stock.

The normal position of the lever 12 is preferably a horizontal one as appears in Fig. 1. The cone 8 is adapted in this normal position to rest with its beveled tip 15 resting within a perforation 16 of a clutch disk 17 being operated upon. This clutch disk is represented in broken lines in Figs. 1 and 2 and it is adapted to seat upon a rest 18 at one end, which rest is carried by the table 1 and may be bolted or otherwise secured thereto and may have a sliding adjustment along the table if desired to bring it to a variety of positions suitable for supporting various styles of clutch disks. The table also carries a pair of set screws 19 having conical or pointed upper ends to engage beneath the disks 17 at opposite sides of a perforation 16, the set screws being adjusted and held in the adjusted position by the use of lock nuts 20. The set screws 19 are spaced appropriately from the rest 18 to receive opposite diametric portions of the disk.

The cone 8 is hollow as indicated in Figs. 4 to 8 inclusive, and the cone carrier is offset above to permit of the placing in the upper end of the cone of a cork or other insert 21 destined for insertion in the opening 16 of the clutch disk. A plunger 22 is slideable through the hollow cone 8 and

acts to drive the cork or other insert into place. This plunger 22 receives its operation manually from a lever 23 pivoted at 24 upon the head stock and being arrested 5 in its downward movement by a laterally projecting stop 25 also on the head stock. The lower position of the lever 23 is also a horizontal one and the arrangement and relative dispositions of the levers 12 and 23 10 is such that upon the depressing of the lever 23 the hand of the operator will thereby be brought close to the normal horizontal position of the lever 12 enabling the latter to be readily grasped and lifted to elevate 15 the cone 8. The lever 23 is coupled to the plunger 22 as by the use of an inverted L-shaped link 26 pivoted to an intermediate part of the lever 23 as indicated at 27 and at its upper angled end between the forks 20 of a yoke 28 as shown at 29. The yoke-piece 28 may be screw-threaded or otherwise secured to the plunger 22. The coil spring 30 has its intermediate portion turned into a suitable number of convolutions about the 25 pivot pin 27, having one end 31 hooked about one edge of the link 26 and the other end 32 about the opposite edge of the lever 23, thereby acting to elevate the lever 23 and the parts associated therewith.

In the operation of the invention, the parts are normally in the position shown in Fig. 4 where both the cone and the plunger are illustrated as normally raised. The disk 17 is then put in place so that the two 35 set screws on opposite sides of the horizontal flanges of the table 1 will receive the clutch disk and support a perforation 16 therein between the set screws and in vertical registry with the descending cone 8 40 whereby the beveled tip 15 thereof may be enabled to center itself upon the rim of the perforation 16. The arrangement of these parts is then such that the cone will hold the disk against casual lateral movement during the operation of introducing 45 the insert.

The cork, in the form of a small cylinder 21, is then placed in the upper end of the cone as indicated in Fig. 5, into which it 50 fits readily. The plunger 22 is then brought down by use of the lever 23 with sufficient pressure to drive the insert 21 down into the gradually reduced portion of the cone which compresses the insert and restricts its diameter so that it is prepared for entry into the small perforation 16 into which it is 55 subsequently driven as indicated in Fig. 7, by the continued downward action of the plunger 22. The plunger is arrested by the abutment of the lever 23 against the stop 25 and this occurs at a point when the insert 60 has been correctly placed, said point being previously determined by adjusting the length of the plunger 26 at 28. The hand of 65 the operator is then close to the lever 12

so that by grasping the same it raises it and with it cone 8. As the lever 23 keeps the plunger 22 in a steady position upon the top of cork (or insert) 21, the raising of cone 8 70 releases the balance of the insert which now spreads out on both faces of the disk and may be afterwards cut or trimmed in any suitable manner. Fig. 8 shows cone 8 being raised while plunger 22 keeps the insert 21 in place, the top of the insert spreading out as soon as cone 8 has been raised 75 sufficiently.

From the foregoing it will be understood that a compact and inexpensive machine having a relatively great capacity for work 80 is produced.

It is obvious that various changes and modifications may be made in the details of construction and design of the above specifically described embodiment of this invention without departing from the spirit thereof, such changes and modifications being restricted only by the scope of the following claims.

What is claimed is:

1. A cork inserting machine for perforated clutch disks and the like comprising a table, an adjustable support on the table for a perforated clutch disk adapted to permit sliding movement of the disk, means movable toward and from the table for centering the perforations of the disk on the support, said means adapted to receive a cork insert, and a plunger moving through said means for forcing the cork insert into a 100 perforation in the disk, substantially as described.

2. A cork inserting machine for clutch disks and the like comprising a table, vertically adjustable means thereon for receiving a perforated clutch disk between the perforations, a cone movable toward and from the disk and having a tip adapted to engage the edges of the perforations in the disk, said cone adapted to receive a cork 110 insert, and a plunger traveling through the cone for forcing the cork insert into the perforation in the disk, substantially as described.

3. A cork inserting machine for clutch disks and the like comprising a table, a head stock carried thereby and having a sleeve, a stationary cone movable toward and from the table adapted to receive a cork insert or the like and provided with a hollow stem sliding in said sleeve, a plunger movable through and independently of the sleeve and through the cone, and independently operable members carried by the head stock for shifting the cone and plunger, substantially as described.

4. A cork inserting machine for clutch disks and the like comprising a support, a head stock thereon, a cone carrier adjustable in the head stock, a lever for adjust-

ing the cone carrier, a cone supported by said cone carrier, a plunger moving through the cone independently of the movement of the cone carrier, and a lever carried by the 5 head stock for the operation of said plunger said two levers being independent in movement the one of the other, substantially as described.

5. A cork inserting machine for clutch 10 disks and the like comprising a support for a clutch disk, a head stock on the support, a cone carrier adjustable vertically in the head stock and having a hollow cone open at both ends for the insertion of an insert, 15 a lever carried by the head stock for the operation of the cone carrier, said cone carrier and lever adapted to descend by gravity into an operative position, a plunger reciprocating through the head stock and cone, 20 a normally raised lever for operating said plunger, said last named lever being disposed above the first named lever and being adjacent thereto when in its lower position, and stop means for the levers in their lower 25 positions carried by said head stock, substantially as described.

6. A cork inserting machine for perforated clutch disks and the like comprising a table,

an elongated support at one portion of the table to receive one part of the disk, spaced 30 supports at a distant portion of the table being adjustable toward and from the table and adapted to receive a substantially diametric part of the disk and to sustain the latter at opposite sides of the perforations in said disk, and means to insert corks in the perforations of the disk while upon 35 said supports.

7. A cork inserting machine comprising a table, supports thereon for a clutch disk or 40 the like, a head stock on the table having a stationary sleeve, a hollow stem sliding in said sleeve, a cone carrier connected to said stem and having a slotted lug, a cone removably carried by said cone carrier, a lever fulcrumed on said head stock and having a pin 45 slidingly engaging said slotted lug, a plunger moving through said hollow stem and cone, a link coupled to the upper end of said plunger and depending alongside the 50 plunger, a second lever fulcrumed on the head stock above said first lever and pivotally coupled to the lower end of said link, the lever adapted to approach closely to one another but being independently operable.

CHARLES BÖISSET.
